COMBINED CARPET FASTENER AND BINDER

Torkel Jaasund, Brooklyn, N. Y., assignor to
General Carpet Supply Co. Inc., New York,
N. Y., a corporation of New York

Application November 15, 1950, Serial No. 195,881

5 Claims. (Cl. 16—5)

1

This invention relates to new and improved means for fastening and binding carpets and has particular reference to a simple and efficient means whereby carpets can be accurately laid on the floor of a room without the use of tacks, and without the need of having the edges thereof especially bound. An object of the invention is to provide a simple and efficient device whereby the carpet can be easily and accurately laid on the floor, preferably over a liner to have its edges securely gripped along their length and then so manipulated as to stretch the carpet taut over the liner without the use of tacks.

A further object is to provide a simple and efficient device whereby the liner can be accurately disposed on the floor and held in position beneath the carpet without any danger of its moving with respect thereto.

Further and more specific objects, features and advantages will more clearly appear from a consideration of the detailed specification herein-after set forth, especially when taken in connection with the accompanying drawings which illustrate a present preferred form which the invention may assume, and which form part of the specification.

In brief and general terms, the invention includes a boundary strip, adapted to be nailed on the floor with one edge spaced at predetermined distance from the wall board, and the other edge adapted to lie in abutment with the outer periphery of a carpet liner. Preferably, the depth of the boundary strip is substantially equal to the depth of the liner so that their top edges lie in the same plane.

The boundary strip has associated with its top surface, a carpet-edge gripping element which may be a series of separate elements, or a single elongate gripping element preferably U-shaped with the ends thereof extending toward the edge of a carpet to be engaged thereby and having carpet-gripping teeth on their inner edges. This series of gripping elements, or the single gripping element, is preferably supported above the surface of the boundary strip by a series of flexible connecting members in the form of spaced strips.

The gripping element is preferably disposed and supported above and along the edge of the boundary strip nearest the wall, and after the ends of the gripper element have engaged the edge of the carpet, repeated impacts of a tool downwardly thereon will cause it to be bent downwardly and backwardly against the adjacent wall or baseboard to assume a reversed position in the shallow recess formed between the baseboard and the boundary strip. This bending movement is permitted by reason of the flexibility of the connecting strips which support the gripping element above the boundary strip. As the gripping element is thus bent backwardly and its position reversed, the tendency of this movement will be to stretch the carpet taut over

2

the top of the liner and the top of the boundary strip.

The preferred form which this invention may assume is shown in the drawings, of which:

5 Fig. 1 is a perspective view of the boundary strip shown fastened to the floor, and in relation to the wall of the room ready to receive and bind the edge of the carpet;

10 Fig. 2 is a partial plan view of the blank from which the strip is formed;

Fig. 3 is a vertical section showing the boundary strip in position with the edge of the carpet related to the gripper means;

15 Fig. 4 is a similar view showing the carpet engaged by the gripper means and the manner in which said means is bent over backward to lie in the recess between the boundary strip and the wall of the room; and,

20 Fig. 5 is a similar view showing the parts in their ultimate position.

25 Referring now merely to the specific construction of the device shown in the drawings, which represents merely one form which it may assume, it will be seen that I provide a simple and efficient device in the form of a boundary strip which is fastened to the floor of a room, spaced a definite distance from the baseboard thereof, and in definite relation to a carpet lining which is disposed on the floor, and over which the carpet is to be placed.

30 In the preferred form, this boundary strip is shown as a U-shaped metal plate 10 having dependent legs 11 and 12 which hold its top surface a definite distance above the floor 13 of the room. This distance is preferably substantially equal to the thickness of the carpet liner 14 so that the top of the liner is flush with the top of the boundary strip 10. This boundary strip may be fastened to the floor by any suitable means such as nails 15. This strip is of a length at least equal to the length of the edge of the liner which is disposed in abutment therewith, and the strip is also disposed a predetermined distance away from the baseboard 16 of the room in order to provide a recess between the strip and the baseboard to be used as and for the purposes subsequently set forth. It is of course understood that a similar boundary strip is related to each of the four edges of the lining, especially where those edges are disposed along and in relation to a wall or baseboard of the room.

35 The boundary strip 10 has associated therewith a gripper element which, in the form shown, takes the form of an elongate U-shaped member 17 which is disposed with its limbs in open spaced horizontal direction facing toward the edge of the carpet to be received therebetween. The ends of the limbs of this gripper element 17 are provided with teeth 18 and 19 projecting therefrom toward each other. This gripper element 17 is supported, in the form shown, above the top of

the boundary strip 10 preferably at the rear edge thereof by means of flexible strips 29. This binder element is also formed with slots 21 in line with the strips 20 to make it more flexible and with apertures 22 adjacent one edge thereof to permit the reception of the end of a tool such as a chisel or a screw driver to enable the limbs of the gripper element to be firmly and definitely pressed against the edge of a carpet inserted therein. The use of such a tool is shown in Fig. 3 in which the tool 23 is indicated in dotted lines. The end of this tool is related to the openings 22 and the top limb of the gripper element so that as the tool is hammered, the upper limb is forced down toward the lower limb of the gripper element to firmly engage the teeth of the gripper element with the edge of a carpet 24 which has been inserted therein.

In Fig. 3 I have shown the carpet in one position thereof in dotted lines to show that when it is laid on top of the liner, its outer edge rests on top of the gripper element and abuts the baseboard 16. In operation, the edge is drawn back and then inserted between the jaws of the gripper element and clamped therein. After the edge of the carpet has been firmly clamped, the gripper element is further subjected to blows of the tool to cause it to be bent backward around the flexible supporting strips 29. As this occurs, the gripper element will be forced against the baseboard and will automatically be bent around into a reverse position as shown in Fig. 4, and with the further impact of repeated blows will assume the ultimate position where it is completely reversed and lying flat within the recess formed between the boundary strip and the baseboard.

It will thus be seen that the first operation relates to the gripping of the carpet edge, and that further manipulations due to impacting blows will cause the gripper element to be bent down and turned completely around. The effect of this will be to very firmly grip the carpet edge and also to pull it taut along the entire edge of the carpet engaged by the gripper means so that the carpet as shown in Fig. 5 is drawn taut and flat across the top of the liner and the top of the boundary strip. This simple and efficient means permits the liner, and subsequently the carpet, to be very accurately disposed in position and to be very properly related to each other and to be held in firm, taut position without having to use tacks or other similar devices.

While the invention has been described in detail and shown with respect to the accompanying drawings, it is not to be limited to such details, since many changes and modifications may be made in the invention without departing from the spirit and scope thereof. Hence, it is desired to cover any and all forms and modifications of the invention which may come within the language and scope of any one or more of the appended claims.

I claim:

1. A combined carpet fastener and binder which comprises a boundary strip to be nailed to the floor co-extensive with one edge of the carpet, an elongate bendable U-shaped gripper element having opposed sets of teeth to engage the edge of the carpet, and flexible means supporting the gripper element above the binder strip, said boundary strip being disposed parallel to and at predetermined distance from an adjacent wallboard to provide a recess into which the gripping element and its flexible supporting means may be reversely bent after the carpet

75
edge has been gripped whereby the carpet is fastened and stretched taut over the boundary strip.

2. A combined carpet fastener and binder which comprises an elongate boundary strip adapted to be disposed with one edge spaced a predetermined distance from and parallel to a wallboard, an elongate U-shaped toothed gripping element disposed above said boundary strip with its spaced limbs facing away from said wallboard and a flexible connection supporting said gripping element above the top of the boundary strip.

3. A combined carpet fastener and binder which comprises an elongate boundary strip adapted to be disposed with one edge spaced a predetermined distance from and parallel to a wallboard, an elongate U-shaped toothed gripping element disposed above said boundary strip with its spaced limbs facing away from said wallboard and a flexible connection supporting said gripping element above the top of the boundary strip, said flexible connection consisting of a series of flexible strips extending from the rear edge of said boundary strip upwardly to the forward edge of the lower limb of the gripping element.

4. A combined carpet fastener and binder which comprises an elongate boundary strip adapted to be disposed with one edge spaced a predetermined distance from and parallel to a wallboard, an elongate U-shaped toothed gripping element disposed above said boundary strip with its spaced limbs facing away from said wallboard and a flexible connection supporting said gripping element above the top of the boundary strip, said flexible connection consisting of a series of flexible strips extending from the rear edge of said boundary strip upwardly to the forward edge of the lower limb of the gripping element, the free edges of the limbs of the gripping element having spaced teeth extending toward each other.

5. A combined carpet fastener and binder which comprises a U-shaped metal boundary adapted to be nailed on the floor parallel to and at a predetermined distance from a wallboard, the height of said boundary strip being substantially the same as the thickness of a liner to be disposed thereagainst, an elongate U-shaped toothed gripping element supported above the boundary strip to engage the edge of a carpet and a series of flexible connecting strips extending upwardly from the edge of the boundary strip which is to be positioned nearest the wallboard, and connected to the end of the lower limb of the U-shaped gripping element, whereby after the gripping element has been manipulated to engage the edge of the carpet, repeated impacts thereon will cause it to bend downwardly and backwardly with the flexible connecting strips to be reversely positioned against the floor in the recess formed between the floorboard and the adjacent side of the boundary strip.
